UNITED STATES PATENT OFFICE

2,097,521

HEATING DEVICE

Anna M. Haas, Chicago, Ill.

Application March 22, 1934, Serial No. 716,791

1 Claim. (Cl. 219—21)

The invention relates to heating devices and more particularly to electric irons.

It is an object of the invention to provide a heating device which is adapted for the ironing and steaming of fabrics of tubular shape or arranged in ruffles which the ordinary flat iron cannot be applied to.

It is a further object of the invention to provide a heating device where the iron proper may be readily exchanged for an iron of more suitable shape to meet particular requirements in the ironing or pressing of delicate fabrics, ruffles, sleeves and the like.

It is an object of the invention to provide an iron of egg shape form and means for supporting such iron with its longitudinal axis in horizontal position.

To the accomplishment of these and other equally important objects, the invention is described in the following specification, particularly pointed out in the claim forming a part thereof and illustrated in the accompanying drawing, in which:

Fig. 1 is a perspective view of the iron constructed in accordance with my invention.

Fig. 2 is a longitudinal section through the iron proper.

Fig. 3 is a section on the line 3—3 of Fig. 2, and,

Fig. 4 is a side view of a modified form of the iron.

Referring to the several views in the drawing, 10 designates a base plate from which arises at the center thereof a post 11 equipped at the upper end with a threaded socket of standard construction. The iron proper generally designated by 14 is in the form of an oval comprising an upper section 15 and a lower section 16, the line of intersection being along a horizontal plane and the lower section 16 being provided with a rabbet 17 into which fits a lip 18 projecting from the upper section 15. The two sections of the iron have a press-fit relation and when assembled form a unitary part. The two sections are also held together by screws 19 and 20 as is obvious from Fig. 2.

The lower section 16 is formed with a tubular extension 30 to which is secured a contact 12 and a contact 13. The contact 12 is formed with screw threads to be threaded into the upper end of the post 11.

A horizontal partition 21 divides the inner

chamber of the iron in an upper and a lower chamber and closes an insulated tract 22 provided at the inner side of the upper section 15 for the reception of a heating element 23 whose ends are connected by wires 24 and 25 to the annular contacts 12 and 13. The partition 21 is formed with a central aperture 26 for the passage of the wires 24 and 25.

In use the iron is connected by a cord 27 and a plug 28 to a source of electrical energy whereby the heating element 23 is energized so that the iron proper 14 is heated.

A fabric such as 29 which is provided with ruffles is drawn around the iron 14 whereby when the heat acts on the fabric the latter is steamed or pressed.

In the case of having delicate materials where ruffles are present the iron shown in Fig. 4 and generally designated by 31 is used which is formed like a projectile and is composed of an upper section 32 and a lower section 33 secured together in the same way as the iron 14 and having also a tubular extension 34 which is provided with a plug contact 35. Thus in the case of small ruffles or pleats the iron 14 is removed and the iron 31 is put in place on the post 11. The fabric is then drawn across the iron 31 and exposed to the influence of the heat emanating therefrom to obtain a pressing or steaming effect.

It is obvious that the shape of the irons and the method of supporting them are suitable for the pressing of sleeves, pleats, ruffles and especially of materials which are delicate or of a frangible nature.

While the drawing shows preferred embodiments of the invention, numerous changes and variations may be made without departing from the spirit of the invention. I, therefore, do not limit myself to details of construction, but claim my invention as broadly as the state of the art permits.

I claim:

In combination with a base plate, a post integral therewith and upstanding therefrom, a socket at the upper end of said post, a heating body of elliptical form constructed with a ball shaped extension at the end, and a plug secured to the underside of said heating body for removable attachment to said post, said heating body having the heating element adjacent to its upper wall and screened from the lower wall.

ANNA M. HAAS.
